(57) **CLAIM**

The ornamental design for a game controller, as substantially shown and described.

DESCRIPTION

FIG. 1 is a top perspective view of a game controller showing my new design;

FIG. 2 is a bottom perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a right side elevational view thereof; and,

FIG. 8 is a left side elevational view thereof.

The broken lines illustrate environment and forms no part of the claimed design.

Structure illustrated in broken lines is provided to illustrate the environment of the invention but is not otherwise part of the claimed design.

1 Claim, 4 Drawing Sheets
